(57) **CLAIM**

We claim the ornamental design for a ring grip nozzle, as shown and described.

DESCRIPTION

FIG. 1 is a perspective view of the ring grip nozzle. FIG. 2 is a left elevation view of the ring grip nozzle of FIG. 1.

FIG. 3 is a right elevation view of the ring grip nozzle of FIG. 1.

FIG. 4 is a front elevation view of the ring grip nozzle of FIG. 1.

FIG. 5 is a rear elevation view of the ring grip nozzle of FIG. 1.

FIG. 6 is a top view of the ring grip nozzle of FIG. 1; and, FIG. 7 is a bottom view of the ring grip nozzle of FIG. 1. The broken lines shown in FIG. 5 shows a portion of the ring grip nozzle that forms no part of the claimed design.
